(57) **CLAIM**

The ornamental design for golf ball putting return apparatus, as shown.

DESCRIPTION

FIG. 1 is a top plan view of the golf ball putting return apparatus showing my new design;

FIG. 2 is a right side elevational view thereof with the left side view being identical but reversed;

FIG. 3 is a front elevational view thereof; and,

FIG. 4 is a back elevational view thereof.

The bottom view is not shown as such is not part of the claimed design.
